CLAIM

The ornamental design for a cover of a fluid control valve assembly for fire protection systems as shown and described.

DESCRIPTION

FIG. 1 Is A Front Perspective View Showing a cover of a fluid control valve assembly for fire protection systems In Accordance With A First Embodiment of Our New Design; FIG. 2 Is A Front View thereof; FIG. 3 Is A Left Side View thereof; FIG. 4 Is A Right Side View thereof; FIG. 5 Is A Top View thereof; FIG. 6 Is A Bottom View thereof.

FIG. 7 Is A Front Perspective View showing a cover of a fluid control valve assembly for fire protection systems In Accordance With A Second Embodiment of Our New Design; FIG. 8 Is A Front View thereof; FIG. 9 Is A Left Side View thereof; FIG. 10 Is A Right Side View thereof; FIG. 11 Is A Top View thereof; FIG. 12 Is A Bottom View thereof.

FIG. 13 Is A Front Perspective View Showing a cover of a fluid control valve assembly for fire protection systems In Accordance With A Third Embodiment of Our New Design; FIG. 14 Is A Front View thereof;

(Continued)

FIG. 15 Is A Left Side View thereof;

FIG. 16 Is A Right Side View thereof;

FIG. 17 Is A Top View thereof; and,

FIG. 18 Is A Bottom View thereof.

The Back View of each of the First, Second and Third Embodiments does not constitute part of the claimed design. The shading lines in the drawings show contour and are not intended to indicate surface ornamentation.

The broken lines in the figures illustrate portions of the cover of a fluid control valve assembly for fire protection systems that form no part of the claimed design.
